UNITED STATES PATENT OFFICE.

HENRY JOHNSON, OF DETROIT, MICHIGAN.

REFRIGERATOR.

No. 872,655.

Specification of Letters Patent.

Patented Dec. 3, 1907.

Application filed October 29, 1904; Serial No. 230,462.

To all whom it may concern:

Be it known that I, HENRY JOHNSON, a citizen of the United States of America, residing at Detroit, in the county of Wayne 5 and State of Michigan, have invented certain new and useful Improvements in Refrigerators, of which the following is a specification, reference being had therein to the accompanying drawings.

- 10 This invention relates to that type of refrigerator in which a cabinet is provided with a top compartment for holding ice to keep the interior cool for preserving articles of food placed in a compartment below and 15 my invention has for its object to make it more handy and convenient to replenish the cabinet with ice and collect and remove the drip therefrom and also to facilitate keeping it clean and in a sanitary condition.
- 20 To this end my invention embodies certain improvements in the construction, arrangement and operation of the compartment for keeping the ice, in the means for collecting and removing the drip from the melting ice, 25 and the means for promoting a circulation of air inside the cabinet all as more fully hereinafter described and shown in the accompanying drawings, in which

Figure 1, is a vertical section in a plane 30 parallel to the front face of the cabinet substantially as indicated by the line $x-x$ in Fig. 2; Fig. 2, is a vertical section in a plane at right angles to Fig. 1 as indicated by line $y-y$ in Fig. 1; Fig. 3, is a detached plan of 35 the ball valve in the bottom of the ice pan; Fig. 4, represents the trapped outlet of the drip pipe as shown in Fig. 1 on a larger scale.

A represents the cabinet built with heat insulating walls, top and bottom in the usual 40 manner, B represents the door in front giving access to the whole interior, C are cleats secured to the end walls of the cabinet for supporting a suitable open work partition C' adapted for the storage of provisions dividing the interior into a top compartment D and a storage compartment E, the latter of 45 which may be provided with shelves in any desired manner.

The top compartment is provided in one 50 of the sides of the cabinet with a door F giving access to the compartment and G is an ice pan removable and insertible through this door. This pan occupies the rear portion of the top compartment and is of suitable size and form to receive and hold the 55 usual supply of ice given a cabinet of this de-

scription. The position of the pan within the compartment is fixed by means of two parallel angle guide rails a and the pan is formed on the underside with corresponding 60 parallel guide flanges b which ride upon the guide rails and guide the pan in withdrawing and inserting it through the door.

In the bottom of the ice pan near the back wall of the cabinet a drip opening c is formed 65 which leads into a conical cup d inclosing a ball valve e all so arranged that the valve when free to seat itself prevents the dripping. When the pan is in position however this ball is upheld by means of an upwardly curved 70 cross bar f placed in the funnel shaped mouth of the waste pipe H which receives the drip from the ice pan and discharges it through an outlet below the bottom of the cabinet into a drip pan I . The position of the drip pan below the waste pipe is also fixed by means of parallel angle guide bars g which support it above the floor removable and insertible endwise through an opening provided in the skirting, the opening being hidden by a piece 75 h of the skirting being fastened to the drip pan and carrying a suitable handle i .

The drip pan is closed on top except for a small portion at the rear side below the outlet from the waste pipe. This outlet is 80 trapped by means of a cup j which is mounted upon the end of a lever k pivotally suspended at l from the bottom of the cabinet. This lever is pressed by a spring s the tension of which operates to press the cup j 85 firmly against the outlet of the waste pipe and thereby seal the same against the discharge of the drip, a flexible washer m being placed upon the bottom of the cup to form a tight seal. When the drip pan however is 90 in position the raised margin n around the opening on the top of the drip pan engages under the free end of the lever and thereby lowers the cup and holds the outlet open, the cup acting merely as a trap, but whenever the drip pan is withdrawn for the purpose of emptying it, the outlet is kept closed 95 and thus the drip is prevented from wetting the floor. By closing the drip pan on top there will be little liability of spilling any 100 water in withdrawing it.

To provide for an efficient circulation of the air within the cabinet, I make the front wall of the ice pan lower than the rest, thus directing the cooled air to pass down over 110 the top of this lower wall and create an ascending current which passes to the top

of the cabinet through the space *o* left between the rear wall of the ice pan and the cabinet. By stopping up the upward passage of air in the space left between the ice 5 pan and the door *F* by a cut-off *p* over this space and by making the ice pan long enough to extend against the opposite wall of the cabinet, no disturbing air currents can arise.

My construction is simple and the devices 10 described make it very convenient to attend to the refrigerator, the advantages of my removable ice pan in a sanitary sense will also be easily recognized. It will be seen that the waste pipe has no bends and can 15 readily be cleaned its whole length from above and the ball *e* is also removably held in place by fingers *v* made of flexible metal strips or the ball may be otherwise removable.

20 Having thus fully described my invention, what I claim is:—

1. In a refrigerator, an ice pan freely insertible and withdrawable therefrom, a drip nozzle depending from the under side of the 25 icepan and adapted to discharge the drip therefrom and a ball valve in said nozzle controlling the outlet therefrom and adapted when seated to project below the discharge end of the nozzle.

30 2. In a refrigerator having its cabinet horizontally divided into an upper and a lower compartment, the combination of an ice pan in the upper compartment freely insertible and withdrawable through an 35 opening in one side of the cabinet, a door closing said opening, parallel guides on the bottom of said compartment adapted to support and guide the ice pan into position within the compartment, a drip nozzle projecting from the underside of the pan in 40 position to conduct the drip from the ice pan into a waste pipe below, a ball valve in said nozzle controlling the outlet therefrom and adapted when seated to project below 45 the nozzle and means adapted to unseat the ball valve when the icepan is in position.

3. In a refrigerator having its cabinet horizontally divided into an upper and a lower compartment, the combination of an 50 icepan extending within the rear portion of the upper compartment freely insertible and withdrawable through a door opening in the side of the cabinet, parallel guides upon which said ice pan is supported in pre-

scribed position within the compartment, a 55 drip nozzle projecting from the underside of the pan near its rear wall, a waste pipe fixed in position beneath the ice pan to receive the drip from said nozzle, a ball valve adapted to seat within the discharge end of the nozzle 60 and project below the nozzle when seated, and an arched bar fixed above the inlet of the waste opening and adapted to uplift the ball from its seat.

4. In a refrigerator, the combination with 65 the cabinet having a horizontal open work partition dividing the cabinet into an upper and a lower compartment, the upper compartment being provided with a door at one end, an ice pan within the rear portion of 70 the upper compartment and adapted to be spaced from the walls thereof, parallel guides adapted to removably support said ice pan and space the same from the walls of the upper compartment in prescribed position 75 within the compartment, said ice pan formed with a front wall of lower height than its sides and ends and having the space between its rear wall and that of the cabinet in communication with the space above and 80 below the ice pan, a projection at the top of the ice pan at one end adapted to close the space between it and the adjacent end of the upper compartment and a cut-off at the opposite end of said upper compartment 85 adapted to correspondingly close the space between it and the ice pan, said end of the compartment being provided with a door for the removal of the ice pan.

5. In a refrigerator having its cabinet 90 divided into an upper ice compartment and a lower storage compartment, an ice pan removably supported in guides within the upper compartment, a waste pipe below the ice pan and an automatically operating 95 valve controlling the passage of the drip from the ice pan into the waste pipe, said valve adapted to close automatically when the ice pan is removed, and means to automatically open said valve when said ice pan 100 is returned into its prescribed position in the cabinet.

In testimony whereof I affix my signature in presence of two witnesses.

HENRY JOHNSON.
